UNITED STATES PATENT OFFICE.

WILLIAM EVAN ROBERTS, OF PORTLAND, OREGON.

GAS-ENGINE VALVE.

1,100,151.

Specification of Letters Patent. Patented June 16, 1914.

Application filed January 9, 1911. Serial No. 601,602.

To all whom it may concern:

Be it known that I, WILLIAM EVAN ROBERTS, a subject of the King of England, residing at Portland, in the county of Multnomah, State of Oregon, have invented certain new and useful Improvements in Gas-Engine Valves, of which the following is a description, reference being had to the accompanying drawing and to the letters and figures of reference marked thereon.

The invention relates to new and useful improvements in rotary valves for gas engines, and more especially to valves of this type which are water cooled.

15 An object of the invention is to provide a rotary valve with a water chamber which separates the gas supply chamber from the exhaust ports.

A further object of the invention is to 20 provide a rotary valve with a central gas supply chamber and radial ports arranged so as to bring said central gas supply chamber into connection first with one cylinder and then another, in a multiple cylinder gas 25 engine, and a third radial port connecting said central gas chamber with a supply pipe.

These and other objects will in part be 30 obvious, and will in part be hereinafter more fully described.

35 In the drawings which show by way of illustration one embodiment of the invention; Figure 1 is a central section through a gas engine having my improved water cooled rotary valve applied thereto. Fig. 2 is a sectional view on the line A, A, of Fig. 1, with the lower part of the engine broken away. Fig. 3 is a sectional view through the valve and valve chamber on the line B, B, of Fig. 1, certain parts being broken 40 away. Fig. 4 is a similar view with the valve rotated through one quarter revolution.

In the drawings, I have illustrated a gas engine consisting of two cylinders 2 and 3, 45 which are connected with a suitable crank casing at the lower end, and with a valve chamber at the upper end which is formed in the cylinder head 4 and valve cover 14. Located within the valve chamber is a valve 50 1 which is cylindrical and has extended ends or journals 5, 5', which are mounted and rotate in suitable bearings in the end of the valve chamber. The valve 1 is provided with a water cooling chamber 7 which extends substantially the entire length of the 55 valve and is suitably connected through the

journals 5, 5', which are hollow, with water pipes 8, 8'. Unions 6, 6', are provided so as to allow the valve to rotate freely independently of the water pipes.

As herein shown, I have provided a beveled gear driving connection between the rotary valve 1, and crank shaft 9 of the engine, and said driving connection, is so proportioned as to rotate the valve once for every two revolutions of the crank shaft. The cylinder 2 is connected with the valve chamber by means of a port 10, and the cylinder 3, is similarly connected through a port 11. These ports allow the free passage of the gas to and from the cylinders. An inlet port 12 is connected with a suitable gas supply 13 through which the admission of fresh gas to the engine cylinders is admitted under the control of the rotary 75 valve 1. Located centrally of the rotary valve, is a gas chamber 18, which is connected to the supply 13 through a radial inlet port 19. A circumferentially disposed chamber 20 connects directly with the radial port 19 and the gas chamber 18 will therefore, be in connection with the supply while said valve is rotating substantially through an arc of 180 degrees.

A radial port 21 leads from the central gas chamber 18 to the outer surface of the rotary valve (see Fig. 1), and when said valve is in proper position, said port in the valve will register with the port 10 leading to the cylinder 2, and said cylinder will thereby be connected with the central gas chamber. A similar radial port 22 (see Figs. 1 and 2) connects the central gas chamber 18 to the port 11 leading to the cylinder 3, when said rotary valve is in proper position. The ports 21 and 22 are so disposed relative to each other, as to supply the cylinders 2 and 3 at the proper time relative to the stroke of the pistons in the respective cylinders.

In the drawings, I have shown the piston 17 operating in the cylinder 2, and the piston 17' operating in the cylinder 3. An exhaust port 15 leads from the exhaust pipe 16 in the cylinder head to the valve chamber. A circumferentially disposed exhaust chamber or passage 23 is arranged to register with the port 10 of the cylinder 2, and connects the same with the exhaust port 15. A similar exhaust chamber or passage 24 connects the port 11 of the cylinder 3 with the exhaust port 15. These exhaust pas-

sages or chambers 23, and 24, are so disposed as to bring the cylinders into connection with the exhaust port at proper intervals in the engine cycle.

5 It will be noted that the exhaust port 15, is located intermediate the two cylinders so that the heated gases passing from the cylinder through the exhaust port, are carried as directly and as quickly as possible from 10 the cylinders to the exhaust pipe 16. It will also be noted that the water chamber 7 lies between the central gas supply chamber 18 and the exhaust chamber in the rotary valve, and will thereby serve to protect as far as possible the supply chamber 15 from the heated exhaust gases. The engine cylinder and valve cover are provided with a water jacket 28 through which water is circulated in the usual manner. Suitable ignition plugs 25 and 26 are shown at the upper ends of the cylinders in Fig. 1. A grease cup 27 is also provided for lubricating the valve 1.

The operation of my device is as follows—Starting with the respective parts in 25 position as shown in Figs. 1, 2 and 3, the chamber or recess 20 in the rotary valve, 1, is connected with the inlet port 12 (see Fig. 3) which allows fresh gas to flow through 30 the radial port 19 and fill the gas chamber 18. As the engine shaft rotates, the valve 1 will also rotate in the direction indicated by the arrow in the drawings and the radial port 22 will register with the port 11, there- 35 by connecting the central gas chamber with the cylinder 3, and as the piston 17' de-scends, gas will be drawn into the cylinder 3. At the completion of this downward stroke of the piston 17', the outer cylindrical 40 surface of the valve 1 will pass over and cover the port 11 and keep it covered or closed during the compression or working stroke of the piston 17'.

During the exhaust stroke of the piston 45 17', the exhaust chamber 24 will be brought into register with the cylinder port 11, thus connecting the port 11 with the exhaust port 15, and permitting the burnt gases to pass from the cylinder 3, out through the exhaust port 15 into the exhaust pipe 16. In 50 Fig. 1, the piston 17 is shown in position for the beginning of its exhaust stroke, and therefore, the exhaust chamber 23 in the valve 1 is in register with the port 10. The 55 burnt gases will therefore, flow from the cylinder 2 through the port 10 and exhaust chamber 23 to the exhaust port 15. At the completion of the exhaust stroke of the piston 17, the gas supply port 21 of the rotary 60 valve 1, will be brought into register with the radial port 10 as shown in dotted lines in Fig. 4.

While the radial port 21 is in register with the port 10 leading to the cylinder 2, 65 the gas supply port 19 through the cham-

ber 20 is connected with the supply pipe 13 thus permitting the piston 17 to draw a charge of fresh gas through the inlet port 12. The compression and working strokes will follow in the usual order.

Having thus particularly described my invention, what I claim as new and desire to secure by Letters Patent, is:—

1. in a gas engine, in combination, one or more cylinders, each provided with a single port extending crosswise thereof and adapted for use as inlet and exhaust port, a valve casing with a chamber therein communicating with said cylinders through said ports and provided in its wall with a water chamber, a rotary valve member mounted in said chamber and having formed in its innermost center, extending longitudinally thereof, a gas chamber with one or more radial ports therefrom, and having formed in its outer surface one or more open, circumferentially extending exhaust chambers, the outer wall of which is formed by the wall of said valve casing, a supply pipe to said central gas chamber, and an exhaust pipe from said valve casing.

2. In a gas engine, in combination with a plurality of cylinders, a valve casing with chamber therein communicating with said cylinders and provided in its wall with a water chamber, a rotary valve member mounted in said chamber and having formed in its innermost center, extending longitudinally thereof, a gas chamber with one or more radial ports therefrom, and having formed in its outer surface one or more open, circumferentially extending exhaust chambers, the outer wall of which is formed by the wall of said valve casing, said valve member also having formed therein, extending circumferentially thereof between said central gas chamber and said outer exhaust chamber, a water chamber directly enveloping said central gas chamber, a supply pipe to said gas chamber, and an exhaust pipe from said valve casing.

3. In a gas engine, in combination with a cylinder, a valve casing with chamber therein in communication with said cylinder and with an exhaust outlet therefrom, a rotary valve member mounted in said chamber and having formed in its innermost center, longitudinally thereof, a gas chamber with radial ports therefrom adapted to be moved into register with the communicating port to said cylinder, a water jacket formed in said valve member and directly enveloping said gas chamber, said valve member also having formed in its outer surface an open, circumferentially extending, exhaust chamber, the outer wall of which is formed by the wall of said valve casing, and a supply pipe to said central gas chamber, substantially as described.

4. A gas engine including in combina- 130

tion, a plurality of cylinders, a cylindrical valve chamber at the upper end of said cylinders, a water jacket extending about said valve chamber, a rotary valve located in 5 said chamber, hollow journals for said valve, bearings for said hollow journals, water pipes, unions for connecting said water pipes to said hollow journals, said valve having a central gas chamber formed 10 therein, radial ports leading from said central gas chamber to each of said cylinders, a radial supply port for connecting said central gas chamber to a supply pipe, and a water chamber extending around said 15 said central gas chamber and connected to said hollow journals.

5. A gas engine including in combination a plurality of cylinders, a cylindrical valve chamber at the upper end of said cylinders, a water jacket extending about said 20 valve chamber, a rotary valve located in said chamber, hollow journals for said valve, bearings for said hollow journals, water pipes, unions for connecting said water 25 pipes to said hollow journals, said valve having a central gas chamber formed therein, radial ports leading from said central gas chamber to each of said cylinders, a radial supply port for connecting said central 30 gas chamber to a supply pipe, a water chamber extending around said central gas chamber, and connected to said hollow journals, and an exhaust chamber formed in 35 said rotary valve for connecting the cylinders

ders with the exhaust pipe, said water chamber being located between said exhaust chamber and said central gas chamber. 35

6. A gas engine including in combination, a plurality of cylinders, a cylindrical valve chamber in the upper end of said cylinders, a rotary valve located in said chamber, hollow journals for said valve, bearings for said hollow journals, water pipes, unions for connecting the water pipes to said hollow journals, said valve having a 40 central gas chamber formed therein, radial ports leading from said central gas chamber to each of said cylinders, a radial supply port in the valve and connecting with said central gas chamber, a fuel supply pipe, 45 said valve having a circumferentially disposed passage formed therein for connecting the radial supply port with the fuel supply pipe, a water chamber extending around said central gas chamber, and connected to 50 said hollow journals, and circumferentially disposed exhaust chamber formed in said rotary valve, and connecting the cylinders with the exhaust pipe, said water chamber being located between the exhaust chamber 55 and said central gas chamber. 60

In testimony whereof I affix my signature, in presence of two witnesses.
